UNITED STATES PATENT OFFICE.

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY.

WAX-THREAD SEWING MACHINE.

Application filed December 21, 1922. Serial No. 608,140.

The invention relates to hook needle wax thread sewing machines, and more particularly to the means for heating the looper of such machine.

5 The object of the invention is to provide a simple and efficient construction of looper heating means, and also a construction which will permit the use of either steam or electricity as the heating medium, and also enable the change from one to the other to be readily made. To these ends the invention comprises the features of construction and combination of parts hereinafter described and referred to in the claims.

15 The invention will be understood from the accompanying drawings in which Fig. 1 is a left hand side elevation showing so much of an inseam sewing machine as is necessary to illustrate the application of the present invention thereto, Fig. 2 is a detail view showing the looper heating means, Fig. 3 is a front elevation of the parts shown in Fig. 2, Fig. 4 is a detailed view partly in section showing the manner of mounting and heating 25 the looper lever, Fig. 5 is a sectional detail on line 5—5, Fig. 6 is a sectional detail on line 6—6, Fig. 7 is a detailed elevation showing means for using steam as the heating medium, Fig. 8 is a front elevation 30 of the construction shown in Fig. 7, Fig. 9 is a detail view partly in section showing the heating means, and Fig. 10 is a sectional detail on line 10—10, Fig. 7.

The invention is illustrated as applied to 35 a welt and turn sewing machine having the general construction and mode of operation of the machine shown and described in Patent No. 1,108,560, dated August 25, 1914. The machine is provided with the curved 40 hook needle 2, the thread finger 4, the welt guide or back gage 6, the looper 8, and the usual cooperating devices for forming the stitches and feeding the work. The looper is secured in the lower end of the looper lever 10 which is pivotally supported on the forward end of the looper slide 12. The slide is reciprocated to give the looper a forward and backward movement by a cam on the cam shaft 14 of the machine and the 45 looper is rocked laterally about its pivot by an oscillating arm 16 which is connected with the looper by a pin 18 passing through a sleeve 20 on the upper end of a stud 22 which

fits within a socket in the upper end of the looper lever.

55 In applying the preferred form of the present invention to the above machine the looper lever is mounted on a hollow shaft carried by the looper slide and adapted to receive within its bore a heating unit which may be adapted for the use of a heating fluid such as steam, or for the use of electricity as the heating medium. As shown the looper lever is mounted on a hollow shaft 24 to which it is secured by a locking bolt 26, and the shaft is journaled in a block 28 secured to the looper slide 12 by bolts 30. The bearings for the shaft embrace the looper lever so that the shaft and lever reciprocate with the looper slide. The looper lever is heated by a cylindrical heating unit adapted to fit within the bore of the hollow shaft and held in fixed position during the reciprocation and oscillation of the shaft and looper lever. This unit may be an electric heating 70 unit as indicated in Figs. 1 to 6 or may be a steam heating unit as indicated in Figs. 7 to 10 and either unit may be applied to or removed from the machine without disturbing the looper and without inconvenience or the 75 exercise of any degree of care or skill.

70 The electric heating unit shown comprises a cylindrical casing 32 adapted to carry a heating core 34 made up of the usual insulated resistance coils and provided with the 80 terminal wires 36. The casing is provided with a laterally projecting stud 38 adapted to be secured in a holder bracket 40. The bracket 40 may be secured by bolts 42 to a bracket 44 which is in turn secured to the 85 frame of the machine by a bolt 46. The heating unit is thus held in fixed position within the hollow shaft during the reciprocation and oscillation of the shaft and looper lever. The holder bracket 40 may be provided with an arm 48 carrying an insulating bushing 50 for guiding and supporting the 90 terminal wires 36 of the heating unit. The wires may lead through an insulating and protecting conduit 52 to a junction box 54 where they are connected through terminals 56 with the lead wires 58 of the electric heating system. The junction box may be conveniently secured upon a stud 60 which is 95 secured in the upper end of a passage 62 formed in the frame of the machine and uti- 100 105

lized as a steam passage when the machine is provided with a steam heating system. In order to heat the bracket 44, as well as parts of the looper operating mechanism, the bracket is provided with a chamber 64 extending back of the arm 16 and pin 18 and adapted to receive an electric heating unit 66, the terminal wires 68 of which may be connected with the terminals 56 in the junction box.

The manner of installing and utilizing a steam heating system for heating the looper is shown in Figs. 7 to 10. The steam heating unit comprises a hollow cylinder 70 adapted to fit within the bore of the hollow shaft 24. The inner end of the cylinder is closed and the outer end is connected with a head 72 provided with a transverse passage 74 which communicates with the chamber 64 within the cylinder 70. The head is secured in a holder bracket 76 which may be secured to the bracket 44 in place of the holder bracket 40 for the electric heating unit and which holds the cylinder 70 in fixed position within the hollow shaft of the looper lever during the reciprocation and oscillation of the shaft and looper lever. Steam may be supplied to the passage 74 and interior of the cylinder 70 through a pipe 78 leading from the outer port of a steam chamber 80 formed within the bracket 44. Steam is supplied to this chamber through a pipe 82 extending from its inlet port in front of the upper end of the looper lever and communicating with a pipe 84 leading from the lower end of the steam passage 62 in the machine frame. In utilizing this system a steam supply pipe 86 is connected with the upper end of the passage and takes the place of the stud 60 which supports the junction box when utilizing the electric heating system.

With the construction and arrangement shown and described either the electric or steam heating system may be readily and conveniently applied to the machine without disturbing the looper or operating parts of the machine and in case it becomes desirable to change from one system to another the change can be readily and conveniently made without the removal or re-adjustment of any of the operating parts. For instance, to change from the electric heating system to the steam heating system it is merely necessary to remove the holder bracket 40, junction box 54 and stud 60 and then secure the holder bracket 76 to the bracket 44 in the

space previously occupied by the bracket 40 and then to make the pipe connections indicated in Figs. 7 to 10.

While it is preferred to employ the specific construction and arrangement of parts shown and described it will be understood that this construction and arrangement may be varied or modified as found desirable or best suited to the construction and arrangement of the parts of the machine to which the invention is to be applied.

What is claimed is:

1. A wax thread sewing machine having, in combination, stitch forming mechanism including a hook needle, a looper, a looper lever, a hollow shaft on which the lever is mounted, a slide in which the shaft is mounted for reciprocating the shaft and lever, and a heating unit adapted to fit within the shaft.
2. A wax thread sewing machine having, in combination, stitch forming devices including a hook needle, a looper, a looper lever, a hollow shaft on which the lever is mounted, an external bearing for the shaft, means for reciprocating the shaft endwise and rocking the lever about its axis, and a stationary heating unit within the shaft.
3. A wax thread sewing machine having, in combination, stitch forming devices including a hook needle, a looper lever, a hollow shaft upon which the lever is mounted, a slide in which the shaft is mounted for reciprocating the shaft and lever, a cylindrical heating unit fitting within the shaft, and means for supplying a heating medium to the unit.
4. A wax thread sewing machine having, in combination, stitch forming devices including a hook needle, a looper, a looper slide mounted for forward and backward movement, a hollow shaft mounted on the slide, a looper lever on the shaft, means for reciprocating the slide and rocking the lever, and a heating unit adapted to fit within the shaft.
5. A wax thread sewing machine having, in combination, stitch forming devices including a hook needle, a reciprocating looper slide, a hollow shaft on the slide arranged to alternatively receive within it heating units constructed for the use of different heating mediums, a looper lever mounted on the shaft, and means for retaining either heating unit within the shaft.

ANDREW EPPLER.
